FIG. 5.

UNITED STATES PATENT OFFICE.

ALBERT STERN, OF YONKERS, NEW YORK.

CONTROLLER.

1,144,872.

Specification of Letters Patent. Patented June 29, 1915.

Application filed March 21, 1914. Serial No. 826,250.

To all whom it may concern:

Be it known that I, ALBERT STERN, a subject of the King of Great Britain, and a resident of Yonkers in the county of Westchester and the State of New York, have invented a new and Improved Controller, of which the following is a full, clear, and exact description.

My invention relates to controllers for electric circuits, and has reference more particularly to a device of the make and break circuit type.

An object of the invention is to provide a simple, compact, efficient and inexpensive controller which combines durability and accessibility of the working parts thereof.

Another object of the invention is to provide a controller which becomes operative when the control lever of the same has reached a predetermined position and has been released.

A further object of the invention is to provide a controller which positively makes and breaks the circuit, the making of the circuit being obtained by prolonged contacts, so as to supply the current through a period of time.

A still further object of the invention is to provide a revoluble controller operable only in one direction and which can be placed in any predetermined intermediate position or brought to its normal position by a continuous movement of the controller's lever.

Another object of the invention is to provide a controller whereby a make and break of the circuit can be made independently of the controlling mechanism whereby normally the make and break of the circuit is obtained.

I attain these objects by a structure disclosed in the accompanying drawings forming a part of the specification, in which similar characters of reference indicate corresponding parts in all the views and wherein—

Figure 1 is a face elevation of the controller embodying my invention; Fig. 2 is a horizontal section on line 2—2, Fig. 3; Fig. 3 is a vertical section on line 3—3, Fig. 2; Fig. 4 is a section on line 4—4, Fig. 3, showing the making of the circuit; Fig. 5 is a plan view of the main ratchet wheel; Fig. 6 is a horizontal section on line 6—6,

Fig. 3; and Fig. 7 is a section on line 7—7, 55 Fig. 4, showing the detail of the contact making mechanism.

Referring to the drawings, 7 represents the support, which preferably forms a slightly raised bottom of a short topless cylinder 8. A tubular standard 9 is mounted in the axis of the cylinder and is rigid with the bottom or support 7, said standard projecting above the open end of the cylinder and forming an axle for the transmission mechanism 10. The transmission mechanism comprises a sleeve 11 mounted to rotate on the standard 9, the lower edge of which is spaced from the support 7 by the shoulder 12 forming part of the standard 70 9. Rigidly secured to the lower end of the sleeve 11 is a pair of disks 13 and 14 which are spaced from each other by means of portions 15 depressed from the disks 14 and forming from said pair of disks a gear, so 75 to say, of which the portions 15 form teeth. The number of teeth formed by the portions 15 is always even and equal to twice the number of signals to be controlled by the device.

The upper end of the sleeve 11 is reduced in diameter so as to form a guide for a coil spring 16 carried by a spring barrel 17 which is mounted to rotate on the sleeve 11 and the standard 9, which standard projects 85 through the centrally apertured upper end 18 of the barrel. The upper end 18 of the barrel rests on the upper edge of the sleeve 11; while the lower open end of the barrel, through where the coil spring 16 is inserted, 90 is made to engage a part of the sleeve 11. By means of this engagement of the lower open end of the barrel and the apertured top end 18, the said barrel is guided properly on said sleeve and standard. The lower end of 95 the barrel is also provided with a flange 19 resting on a shoulder 20 forming part of the sleeve 11, and which shoulder properly spaces said flange 19 from the disks 14 carried by the sleeve 11. The coil spring 16 100 has one of its ends secured to the upper end 18 of the barrel, while the other end of said spring is engaged by a pin 20 rigid with the sleeve 11. The said spring, therefore, couples the transmission mechanism with 105 the spring barrel; and when the transmission mechanism is prevented from movement, the coil spring 16 can be wound by

turning the spring barrel; and when the spring barrel is retained in position and the transmission mechanism has been released, the unwinding of the coil spring 16 will cause the transmission mechanism to rotate. Therefore, it may be stated that the spring 16 forms the motor whereby the transmission mechanism is actuated.

Mounted between the disk 14 of the sleeve 10 and the flange 19 of the barrel 17 is a travel controller 21 formed of a washer 22 mounted to rotate on the shoulder 20 of the sleeve, said washer having a lateral projection 23 which is adapted to abut against a projection 24 formed on the disk 14 by raising a portion thereof, as best shown in Fig. 4. The washer 22 is also provided with an upward vertical projection 25 diametrically opposite the projection 23, which projection 25 engages a cut-out 26 in the flange 19 of the spring barrel 17. This cut-out affords a complete revolution of the transmitting mechanism.

The flange 19 of the spring barrel is provided with a lateral extension 27 forming an arm, at the end of which a spring-actuated pawl 28 is mounted. The movement of said pawl is limited by a cut-out 29 formed in the extension or arm 27 (see Fig. 6). A spring 30, which actuates the pawl, normally tends to force the same away from the barrel so as to engage an indented ring 31 rigidly secured at the open end of the cylinder 8. This indented ring 35 forms the ratchet for the pawl 28. It will be noted that the angular displacement between the indentures 32 is uniform.

Mounted to rotate on the spring barrel 17 is a driving mechanism 33 comprising a sleeve 34 engaging the barrel 17 and through which the barrel projects. The lower end of said sleeve rests on the flange 19 of the spring barrel and thereat having a laterally extending arm 35 which bears 40 with its extremity 36 on the indented ring 31 to form an additional support adapted to relieve the stress on the barrel when the same is set in motion by means of the controlling crank arm 37 which is rigidly secured to the upper end of the sleeve 34. The motion from the driving mechanism to the spring barrel is transmitted by means of a member 38 rigid with the upper end of the spring barrel 17 projecting through the sleeve 34, said member 38 having a laterally extending indicating hand 39 depressed into a slot 40 formed in the controlling crank arm 37, thus coupling the driving mechanism to the spring barrel. In turning 50 the controlling crank arm 37 the spring barrel is caused to turn on the transmission mechanism 10 and the tubular standard 9.

Mounted to rotate on the driving mechanism 33 is a transmission controller 41,

consisting of a sleeve 42 mounted to rotate on the sleeve 34. The sleeve 42, is provided with a ratchet wheel 43 bearing on the arm 35. Adjacent the upper end of the sleeve 42 is a member 44 rigid with the sleeve and having a laterally extending arm 45 which is provided at the end with an elongated slot 46 engaged by a crank 47 which projects through the indented ring 31 into the cylinder 8. To the projecting end of said crank is secured a spring actuated pawl 48. The pawl 48 bears on a pin 49 carried by the support 7, said pin 49 and the engagement of the crank 47 with the indented ring 31 guiding the movement of the pawl 48 on the support 7. The coil spring 48' which influences the pawl 48 normally forces the same toward the lateral surface of the cylinder 8.

The sleeve 34 of the driving mechanism, adjacent the bottom, is provided with a lateral extension 50 which is preferably diametrically opposite the arm 35 of said sleeve. Mounted on said extension 50 is a spring actuated pawl 51 engaging the ratchet 43, whereby the transmission controller 41 is connected to the driving mechanism. It will be noted that the ratchet 43 is indented, as shown at 52, so as to lock the same by the pawl. In turning the driving mechanism 33 the sleeve 42 is carried therewith. Thus the crank 47 is turned, bringing the pawl 48 against the lower disk 13, the edge of which forms a ratchet 53 and whereby the transmission mechanism is prevented from turning until said pawl is released. The slot 40 in the controlling crank arm 37 is sufficiently wide to permit an angular displacement of the driving mechanism to bring the pawl against the ratchet 53 before the same engages the hand 39 whereby the coil spring 16 is wound. The displacement of the controlling crank arm 37 from the position shown in full line in Fig. 1 to the position shown 100 in dotted line in the same figure, brings the pawl 48 against the ratchet 53.

A further movement of the crank arm 37 forces the pawl 51 out of engagement with the ratchet 43, which is prevented from turning further by the engagement of the pawl 48 with the transmitting mechanism. This displacement of the controlling crank arm 37 also forces the pawl 28 out of engagement with the indented ring 31 and thus winds the 110 spring 16. The spring barrel 17 in its movement carries therewith the travel controller 21 due to the engagement of the cut-out 26 with the vertical projection 25 of the travel controller. When the pawl 28 is permitted 120 to engage any of the indentures 32 in the ring 31, the spring barrel 17 is locked to the indented ring 31. Releasing the controlling crank arm 37, the spring 48' will 130 disengage the pawl 48 bringing the other

side of the slot 40 of the crank arm 37 in contact with the indicating hand 39. This disengagement of the pawl 48 with the ratchet 53 leaves the transmission mechanism free to rotate, and the same is turned by the stressed coil spring until the projection 24 on the upper disk 14 brings the vertical projection of the travel control against the straight shoulder 54 of the cut-out 26, hence blocking its further movement. That is to say, in the normal position of the device, as shown in Fig. 1, the pawl 28 engages the indenture 32 in the disk 31. The lateral projection 23 of the travel control abuts against the projection 24 of the transmission. To insure disengagement of the ratchet 53 from the pawl 48 a coil spring 55 is provided under the arm 35 of the driving mechanism. The spring is attached at one end to the extension 50 of the mechanism and with the other end to the lateral extension 27 of the spring barrel 17. The tendency of this spring is to help the spring 48 to disengage the pawl from the transmission mechanism and therefore to always bring the controlling crank arm 37 from the position shown in dotted line in Fig. 1 to the position shown in full line in the same figure.

30 Rotatably mounted on the support 7 is a toothed sector 56 which has a raised portion 57 fitted between the disks 13 and 14 of the transmission mechanism to be engaged by the portions 15. The sector 56 is provided 35 with a second raised portion 58 resting at an insulating pin 59 under the action of a spring 60, shown best in Fig. 7, said insulating pin 59 being carried by the support 7. A toggle 61 of insulating material is rotatably mounted on the support 7 adjacent the raised portion 58 of the sector. A resilient contact member 62 rests against the toggle 61; and a second resilient contact member 63 is normally spaced from the contact member 62 by the engagement of the extremity of said contact member 63 with the insulating pin 59. The toggle 61 is provided with a lateral extension 64 adapted to be engaged by the raised portion 58 of the sector.

50 When the sector 56 is turned on its pivot by the members 15, the spring 60 is wound until the engaging member 15 releases the raised portion 57 of the sector and permits the spring 60 to bring the raised portion 58 of the sector against the pin 59. The extension 64 of the toggle is so positioned that there is substantially no displacement of the toggle when the sector is moved by the transmission mechanism, and, therefore, 55 there is no contact between the contact members 62 and 63. But when the sector is returned to its normal position by means of the spring 60, there is a large angular displacement of the toggle, causing a perfect 60 prolonged contact between the contact mem-

bers 62 and 63, as shown in dotted line in Fig. 4. The contact members and toggle 61 return to their normal position due to the resiliency of the contact members 62 and 63.

To prevent a too rapid movement of the sector 56 under the action of the coil spring 60, a regulator for said spring 60 is formed by providing an escapement which meshes with the sector 56. The escapement consists of a double pawl 65 engaging a ratchet 70 75 66, both mounted on the support 7, and a pinion 67 rigid with the ratchet 66 and in mesh with the sector 56. By means of this escapement, a too short contact between the contact members 62 and 63 is prevented by 80 the spring 60 which causes the contact.

To prevent a too rapid movement of the transmission mechanism under the action of the coil spring 60, an escaping mechanism is provided for the transmission mechanism, 85 said escaping mechanism comprising a double pawl 68 controlling a ratchet wheel 69, both mounted on the support 7, and a pinion 70 rigid with the ratchet 69 and in mesh with a gear 71, which gear is formed 90 by downward depressions in the disk 13 of the transmission mechanism. This escapement regulates the movement of the transmission mechanism.

The contact members 62 and 63 are insulated from the support 7 by which they are carried and from each other by an insulating member 72. The binding posts 73 and 74, which secure said contact members 62 and 63 respectively to the support 7, are also to the under side of the support contacting members 75 and 76 respectively. The contacting members 75 and 76 are located in the recess of the cylinder 8 formed by the raised bottom, which forms the support 7, and are insulated from each other and from said support 7 by an insulating member 77. The contacting members 75 and 76 extend so as to be superposed opposite the bore of the hollow standard 9. A 110 plunger 78 engages the bore of the standard 9. The lower end of the standard is reduced in diameter and receives an insulated bushing 79 which connects said plunger to the contacting member 75 while 115 insulating the same therefrom. The upper end of the plunger projecting through the standard 9 is provided with a head 80 which limits the movement of the plunger in the standard, whereby the engagement of the 120 contacting members 75 and 76 is obtained.

A cap 82 fitting on to the projecting end of the plunger 78 is removably secured thereto by means of a pin 83 (see Fig. 3) which has a single resilient coil engaging a 125 groove 84 formed on the cap. This cap forms a retainer for the plunger 78 in the tubular standard 9, and also a retainer for the spring barrel 17. That is to say, while said cap permits the rotation of the spring 130

barrel, it prevents the axial movement of the same, and it also prevents the removal of the plunger from the standard 9, although it permits its axial displacement 5 for producing the contact between the contacting members 75 and 76, as best seen in Fig. 3.

The mechanism of the controller below the controlling crank arm 37 is inclosed in 10 a casing formed by the cylinder 8 and a cover 85 therefor. The cylindrical portion 86 of the cover fits snugly on to the cylinder 8 to form a smooth exterior, lateral surface, which lateral surface formed by said cylindrical portion 86 of the cover and the cylinder 8, is, in turn, fitted snugly into a cup 87, forming the means whereby the controller can be secured to any suitable place. The cover 85, above the cylinder portion, 20 is provided with an annular shoulder against which the cup abuts. The portion of the cover 85 above the shoulder is so shaped as to make it neat in appearance. The top of the casing is apertured to fit on to 25 the upper end of the sleeve 42 forming part of the transmission controller. The lower face of the controlling arm 37 is provided with an annular recess 88 concentric with the sleeve 34. A soft washer 89 is positioned in said recess whereby the case formed by the cover 85 and cylinder 8 is perfectly closed, thus making the same weatherproof. The top of the cover 85 is also provided with identification means 30 90 35 forming a dial for the controller, and for which dial the hand 39 is an indicator. The angular distance between the identification means 90 is equal to the annular displacement between the indentures 32 in the ring 40 31, between the teeth of the ratchets 53, those of the ratchet 43, and twice the angular distance between the members 15 of the disk 14 in the transmission mechanism. It is understood that the position of the identification means on the cover, that of the indentures 32 of the ring 31, and of the ratchets 53, are properly correlated so that when 45 the pawl 28 is in any of the indentures 32 of the ring 31 the hand 39 is opposite a corresponding identification mark 90 and the pawl 48 ready to engage one of the teeth of the ratchet 53.

From the above description it will be noted that the transmission mechanism is set 55 in motion by the unwinding of the coil spring 16 when the controlling crank arm 37 is released. That is to say, the coil spring 16 must be first energized before the same can turn the transmission mechanism. 60 The same action is necessary for causing the contact between the contacting members 62 and 63, that is, the coil spring 60 which produces the contact must be first energized before the same can produce the contact. It 65 will be further noted that when the con-

trolling crank arm 37 is rotated, the same may be brought to its original position by a continuous rotation before the transmission mechanism is set in motion, the complete revolution being obtained, as previously stated, by provision of the cut-out 70 26 in the flange 19 of the spring barrel. It may also be remarked that if the controlling crank arm 37 is released at any intermediate position between the indentures 32 of the 75 ring 31, the coil spring 16 will force the same back to the nearest indenture 32, when the pawl 48 will release the transmission mechanism. This structure prevents the operation of the device at any intermediate 80 point except those that are previously determined.

The identification characters on the cover 85, as shown in Fig. 1, are represented by the letters O, S, R and L. The reason for 85 this is that the device is intended for use in connection with annunciators to be carried by self-propelling vehicles. The letter O on the contrivance illustrated indicates the neutral or normal position of the same, and, 90 therefore, of the annunciator connected thereto. The letters S, R and L represent "Stop," "Right" and "Left," for indicating the anticipated movement of the vehicle. It will be also noted that when the controller handle is moved from the neutral position, that is, from letter O to any of the other letters, as e. g., the letter R, the annunciator will be operated when the controlling handle is released and the controller 100 will make and break four contacts. For example, the controller crank arm 37 has been set in motion to bring the annunciator to the desired place, and if during its movement it is desired to bring it again to the normal position, that is, to make a complete revolution, the same can be done without any interference therefrom, as has been previously 105 described and stated. Furthermore, assuming that the indicating hand 39 is positioned on the letter S and it is desired to bring the handle to the neutral position, the indicator will continue to revolve in the same direction as indicated by the arrow in Fig. 1. Or, suppose it is desired to move 110 the indicator again to S, it is not necessary in this case to stop the movement of the crank arm 37 at the neutral position, i. e., at O, but the same can be moved to S. Therefore it will be seen that a complete revolution of the controlling crank arm 37 can be made from any position in which the controller finds itself. When the controlling crank arm 37 has been displaced to a desired angle, i. e., to any of the letters, to bring the 115 said arm and, therefore, the contrivance to the neutral or normal position, the revolution of the crank arm must be completed, as the device is only revoluble in one direction.

While the device is mainly intended for 130

use in connection with annunciators for self-propelling vehicles, the same can be used as a transmitter of electric impulses, as, by means of my device, by a predetermined angular displacement of the controlling crank arm 37, a predetermined number of electric impulses is sent. That is to say, if the controlling lever is moved through an angle of ninety degrees, as shown in the accompanying drawing, there will be two impulses. If it is moved through one hundred and eighty degrees, there will be four impulses; and if moved through three hundred and sixty degrees, there will be eight impulses. And, as above stated, the number of four or eight impulses can be made from any desired point in which the controlling arm 37 finds itself. It may also be remarked that while the contrivance herein disclosed shows four predetermined positions of the controlling lever, any other number can be provided, *i. e.*, three, six, eight, or any other number can be made. In all cases, the angular distance between the identification means remains equal. It is self-evident in this case that the indentures in the ring 31, ratchet 53, ratchet 43, and the number of members 15 formed between the disks 13 and 14 in the transmission mechanism, must be correspondingly changed. It is self-evident that the identification marks 90 on the cover will vary in accordance with the use of the contrivance.

By means of the plunger 78, impulses can be sent through the same line without moving the controlling crank arm 37 and the mechanism connected thereto. By means of this plunger, the means controllable by the contrivance herein disclosed are brought in proper relation when the device is set up, or when by any inadvertence the same has become disorganized. As, for example, assuming that the controlling arm is at the neutral position while the annunciator shows "Stop," by actuating the plunger the proper number of times the annunciator is brought to the neutral position, thus corresponding to the position of the controlling arm.

In short, my invention consists of a movable contact, a coil spring having winding and unwinding ends, an operating handle adapted to lock the unwinding end while the winding end is displaced by the handle and release the unwinding end when the winding end is locked, with means for transmitting the movement from the unwinding end to the movable contact.

It is evident that various changes might be made and modifications resorted to in the construction and arrangement of the parts described without departing from the spirit and scope of my invention; hence, I do not wish to limit myself to the exact construction shown.

Having thus described my invention, I

claim as new and desire to secure by Letters Patent:

1. In a circuit controller of the make and break type, a pair of contacts normally tending to remain apart; a member adapted to bring said contacts together; a second member for operating said first member; a spring associated with the second member; and manually operable means associated with the last mentioned member whereby said spring can be energized a predetermined number of times, thus causing a corresponding number of contacts by the engagement of said second mentioned member with said first mentioned member.

2. In a circuit controller of make and break type, a pair of resilient contacts normally tending to remain apart; a toggle bearing against one of said contacts; a member for displacing said toggle whereby the contacts are brought together; manually operable means having a varying range of movement for displacing the member a predetermined number of times by a single displacement of said manually operable means; and a resilient member for restoring the above member to its normal position, the resiliency of said contact member engaging the toggle restoring the same to its normal position after the same has been displaced by said member.

3. In a circuit controller of make and break type, a pair of resilient contacts normally tending to remain apart; an insulated toggle bearing against one of said contacts; a toothed sector having means for displacing said toggle whereby said contact members are brought together; manually operable means having a variable range of movement for displacing the sector, said sector being adapted to be displaced a variable, predetermined number of times by a single displacement of said manually operable means; a spring for maintaining said sector in normal position after the same has been displaced by said manually operable means, said sector displacing said toggle when the same is restored by said spring to its normal position, said resilient contacts being adapted to restore said toggle to its normal position after the same has been displaced by said sector; and an escapement mechanism meshing with said sector whereby the speed of said sector is controlled.

4. In a circuit controller of make and break type, a pair of resilient contacts normally tending to remain apart; an insulated toggle bearing against one of said contacts; a member for actuating said toggle; a resilient member for bringing said member to inoperative position; and means for displacing said member from its inoperative position a predetermined number of times by a single displacement of said means, said toggle and member being so related that when

said member is displaced from its normal position by said means there is substantially no displacement of said toggle, but when said member is restored by the spring to its normal position, a material displacement of the toggle takes place before the same can pass said member, whereby said contacts are brought together.

5. In a circuit controller of make and break type, a pair of resilient contacts normally tending to remain apart; an insulated toggle bearing against one of said contacts; a member for actuating said toggle; a resilient member for bringing said member to inoperative position; and means for displacing said member from its inoperative position a predetermined number of times by a single displacement of said means, said toggle and member being so related that
- 10 when said member is displaced from its normal position by said means there is substantially no displacement of said toggle, but when said member is restored by the spring to its normal position, a material displacement of the toggle takes place before the same can pass said member, whereby said contacts are brought together; and a regulator associated with said member for regulating its movement caused by the spring
- 15 tending to restore said member to its normal position and whereby the contact caused by the toggle is prolonged.
- 20

6. In a circuit controller of make and break type, a pair of resilient contacts normally tending to remain apart; an insulated toggle engaging one of said contacts; a toothed sector having means adapted to displace said toggle; means for angularly displacing said sector; a coil spring for restoring said sector to its normal position after the same has been displaced, said sector and toggle being so related that there is substantially no displacement of said toggle by said sector when the same is displaced by said means, but causing a large displacement of said toggle when said sector is restored to its normal position by said spring, thus causing a prolonged contact between said contact members; and an escapement mechanism in mesh with said sector whereby the speed of the same is regulated when the same is restored to its normal position by said spring, said toggle being restored to its normal position after the displacement of said sector by the resilient contact engaging said toggle.

7. In a circuit controller of the make and break type, a pair of normally separated contacts; means for bringing said contacts together; manually operable means having a variable range of movement for actuating said first means a variable, predetermined number of times by a single displacement thereof; and means for maintaining said manually operable means at different pre-

determined positions, said first means becoming operable when said manually operable means have been released, said manually operable means remaining stationary during the operation of the first means.

8. In a controller, circuit make and break means, including a movable contact and a mechanism for operating the movable contact a predetermined variable number of times, said mechanism comprising a motor, a transmission between the same and the movable contact and an operating handle for energizing the motor, having a variable range of movement, the energy of the motor becoming available and transmitted to operate the contact after the displacement of the handle and its release, said handle remaining stationary during the working of the motor.

9. In a controller, circuit make and break means, including a movable contact and a mechanism for operating the movable contact a predetermined variable number of times, said mechanism comprising a coil spring having a winding and an unwinding end, an operative handle, including means for winding the spring, means controllable by said handle whereby the unwinding end is retained while the winding end is moved by the handle and when the unwinding end is released the winding end is retained, and means for transmitting the movement from the unwinding end of the spring to the movable contact.

10. In a controller, circuit make and break means, including a movable contact and a mechanism for operating the movable contact a predetermined variable number of times, said mechanism comprising a motor, transmission means between the same and the movable contact, an operative handle for energizing the motor, means operable by the initial movement of the handle locking the transmission during the energization of the motor, said means locking the transmission automatically releasing the same when the handle is released, whereby the energized motor actuates the movable contact through the medium of the transmission means.

11. In a controller, circuit make and break means, including a movable contact and a mechanism for operating the movable contact a predetermined variable number of times, said mechanism comprising a spring having a winding and an unwinding end, a spring barrel receiving the spring and engaging the winding end, an operative handle associated with the barrel, transmission means engaging the unwinding end of the spring and adapted to transmit the movement of the spring to the contact, means controllable by the handle whereby the transmission means is locked when the barrel is revolved by said handle and when the

barrel is locked the transmission is released by said handle, the displacement of the barrel by the handle energizing the spring, and the release of the transmission means by the handle after the displacement of the barrel deenergizing the same, whereby the movable contact is operated.

12. In a controller, circuit make and break means, including a movable contact and a mechanism for operating the movable contact a predetermined variable number of times, said mechanism comprising a motor, a transmission mechanism between the same and the movable contact, an operating handle for energizing the motor, said transmission becoming operable when the handle is released, said transmission means including a gear and an escapement mechanism in mesh with said gear for controlling the speed thereof when the same is moved by the motor, said handle remaining stationary during the working of the motor.

13. In a controller, circuit make and break means, including a movable contact and a mechanism for operating the movable contact a predetermined variable number of times, said mechanism comprising a spring having a winding and an unwinding end, a barrel carrying said spring and engaging the winding end, means for locking the barrel in predetermined positions, a transmission mechanism engaging the unwinding end of the spring and adapted to transmit the movement of said end to said movable contact, an operative handle associated with said barrel, means controllable by said handle adapted to lock the transmission mechanism and unlock the barrel, thus retaining the unwinding end, while the winding end of the spring can be moved by the operating handle, said means controllable by the handle releasing said transmission means after said barrel has been locked, whereby the unwinding end of the spring is free to move and operate the movable contact.

14. In a controller, circuit make and break means, including a movable contact and a mechanism for operating the movable contact a predetermined variable number of times, said mechanism comprising a coil spring having a winding and an unwinding end, a spring barrel engaging the winding end of the spring, a transmission engaging the unwinding end, whereby the movement of said end is transmitted to the movable contact, yielding means associated with the barrel whereby the same can be locked in different predetermined positions, an operating handle associated with the barrel, and means operable by the initial movement of the handle whereby the transmission means are locked before the barrel is unlocked by said handle and moved to any desired, different, predetermined position, said means operable by the initial movement of the

handle automatically releasing said transmission mechanism when said barrel is locked and said handle is released, thus permitting the unwinding end to move and operate the contact.

15. In a controller, a casing, a circuit make and break mechanism, including a movable contact in said casing, and a mechanism in said casing for operating the movable contact a predetermined variable number of times, said mechanism comprising a spring having a winding and an unwinding end, a barrel carrying the spring and engaging the winding end, a mechanism engaging the unwinding end and adapted to transmit its movement to the contact, an operative handle associated with the barrel and positioned outside of the casing, whereby said barrel can be displaced through variable predetermined distances and retained in said displaced position, means controllable by said handle whereby said transmission mechanism is locked when said barrel is moved by said handle and whereby said transmission is released when said barrel is retained in position, and means controlling the displacement of said barrel and transmission means after the displacement of the barrel.

16. In a controller, a casing, a circuit make and break mechanism, including a movable contact in said casing, and a mechanism in said casing for operating the movable contact a predetermined variable number of times said mechanism comprising a motor, transmission means from the motor to the movable contact, an operating handle outside of the casing whereby the motor can be energized in different predetermined degrees, and a travel control associated with the motor and the transmission whereby the displacement of the transmission by the motor is controlled.

17. In a controller, a casing, a circuit make and break mechanism, including a movable contact in said casing, and a mechanism in said casing for operating the movable contact a predetermined variable number of times, said mechanism comprising a motor, an operating handle on the outside of the casing for energizing the motor in variable degrees, transmission means from the motor to the movable contact, said transmission means becoming operable after the motor has been energized, and means controlling the displacement of said transmission by the motor.

18. In a controller, a casing, a circuit make and break mechanism, including a movable contact in said casing, and a mechanism in said casing for operating the movable contact a predetermined variable number of times, said mechanism comprising a spring having a winding and an unwinding end, a barrel carrying said spring and en-

- gaging the winding end; a spring-operated pawl carried by said barrel, said casing having a ratchet adapted to be engaged by said pawl and whereby said barrel can be maintained in predetermined positions, a transmission mechanism associated with the unwinding end whereby the movement thereof is transmitted to said movable contact, an operating handle outside of the casing and associated with said barrel whereby the engagement of said barrel with the ratchet can be varied, means operated by the initial movement of the handle locking the said transmission means while the barrel is moved by the handle, said means automatically releasing said transmission means after the barrel has been displaced and the handle released, and means controlling the relative displacement of the transmission means with reference to the barrel.
19. In a controller, a casing, a circuit make and break mechanism, including a movable contact in said casing, and a mechanism in said casing for operating the movable contact a predetermined variable number of times, said mechanism comprising a coil spring having a winding and an unwinding end, a barrel carrying the spring and engaging the winding end, transmission means engaging the unwinding end and adapted to transmit the movement thereof to said movable contact, means carried by the barrel whereby the same is yieldingly locked to the casing, an operative handle outside of the casing and associated with the barrel, means connecting the handle to the barrel so that the same has initial free movement thereon, means associated with the handle and adapted to lock the transmission means by the initial movement of the handle, said transmission remaining locked during the displacement of the barrel, said yielding means being adapted to retain said barrel in any predetermined position when displaced by said handle, said means locking the transmission means automatically releasing the same when said handle is released, and travel control means carried by the barrel whereby a corresponding displacement of the transmission means is obtained to that given by the handle to the barrel.
20. In a controller, a casing, a circuit make and break mechanism, including a movable contact in said casing, and a mechanism in said casing for operating the movable contact a predetermined variable number of times, said mechanism comprising a spring having a winding and an unwinding end, a barrel carrying said spring and engaging the winding end, a spring actuated pawl carried by the barrel, said casing having a ratchet adapted to be engaged by said pawl and whereby the same can be retained in predetermined positions and rotated in a

predetermined direction, a transmission mechanism engaging the unwinding end of the spring and adapted to transmit the movement thereof to the movable contact, transmission travel control means engaging the transmission mechanism and whereby the winding and unwinding ends of the spring are normally maintained in a fixed relation, an operating handle mounted to rotate on said barrel outside of said casing, a member connecting said barrel to the operating handle whereby said handle has an initial movement thereon before it engages the barrel, means associated with the handle where, by the initial movement thereof, the transmission mechanism is locked, remaining so during the displacement of the barrel, said means locking the transmission automatically releasing the same after the displacement of the barrel and release of the handle, which is then set in motion by the unwinding end of the spring.

21. In a controller, a casing, a circuit make and break mechanism including a movable contact in said casing and a mechanism in said casing for operating the movable contact a predetermined variable number of times, said mechanism comprising a spring having a winding and an unwinding end, a barrel carrying the spring and engaging the winding end, a transmission mechanism engaging the unwinding end whereby the movement of the unwinding end is transmitted to the contact, an operative handle associated with the barrel positioned outside of the casing whereby said barrel can be turned through variable angular distances and retained in said displaced positions, means controllable by said handle whereby said transmission mechanism is locked when said barrel is moved by said handle and whereby said transmission is released when said handle is released, and a transmission travel control connecting the transmission to the motor whereby the unwinding end of the spring is displaced the same amount as the winding end has been displaced by the movement of the controller by the handle.

22. In a controller, a casing, a circuit make and break mechanism including a movable contact in said casing and a mechanism in said casing for operating the movable contact a predetermined variable number of times, said mechanism comprising a coil spring having a winding and an unwinding end, a barrel carrying the spring and engaging the winding end, a transmission mechanism engaging the unwinding end whereby the movement of the unwinding end is transmitted to the contact, an operative handle associated with the barrel positioned outside of the casing whereby said barrel can be turned through variable angular distances and retained in said dis-

- placed positions, means controllable by said handle whereby said transmission mechanism is locked when said barrel is moved by said handle and whereby said transmission is released when said handle is released, and a transmission travel control connecting the transmission to the motor whereby the unwinding end of the spring is displaced the same amount as the winding end has been 5
- 10 displaced by the movement of the controller by the handle, said barrel having means whereby a complete revolution of the same can be made by the handle before the transmission means becomes operative by the release of the handle.
- 15 23. In a controller, circuit make and break means including a movable contact and a mechanism for operating the movable contact a predetermined variable number of 20 times, said mechanism comprising a motor, transmission means between the same and the movable contact, an operative handle for energizing the motor, said transmission having a ratchet, a pawl normally disengaged from said ratchet, and means operable by the initial movement of the handle for engaging the pawl with the ratchet of the transmission during the movement of said handle whereby the motor is energized, said 25 30 means energized by the initial movement of the handle releasing automatically the pawl from the ratchet of the transmission when the handle is released, whereby the energized motor actuates the movable contact through 35 the medium of the transmission.
24. In a controller, a casing, a circuit make and break mechanism including a movable contact in said casing and a mechanism in said casing for operating the movable contact a predetermined variable number of 40 times, the mechanism comprising a spring having a winding and an unwinding end, a barrel carrying the spring and engaging the unwinding end, a transmission mechanism engaging the unwinding end and adapted to transmit its movement to the contact, an operative handle associated with the barrel and positioned outside of the casing whereby said barrel can be displaced through 45 50 variable angular distances and retained in said displaced positions, said transmission having a ratchet, a pawl adapted to engage the ratchet, a spring normally disengaging the pawl from the ratchet, a crank for moving the pawl and means connecting the crank to the handle whereby said pawl engages the ratchets of the transmission while the barrel is turned by the handle, said spring disengaging the pawl from the ratchet of the 55 60 transmission when the handle is released, thus leaving the transmission free to move.
25. In a controller, a casing, a circuit make and break mechanism including a movable contact in said casing and a mecha-
- nism in said casing for operating the movable contact a predetermined number of times, said mechanism comprising a spring having a winding and an unwinding end, a barrel carrying the spring and engaging the winding end, a mechanism engaging the unwinding end and adapted to transmit its movement to the contact, an operative handle associated with the barrel and positioned outside of the casing whereby said barrel can be displaced angularly through 65 70 predetermined variable angular distances and retained in said displaced positions, said transmission having a ratchet, a pawl adapted to engage the ratchet, a spring normally disengaging the pawl from the ratchet, a crank whereby the pawl is moved toward the ratchet, a ratchet associated with the handle, an arm associated with the ratchet, engaging the crank, a spring operated pawl locking the second ratchet to the handle, said 75 80 operating handle having means whereby the same has an initial movement on the barrel before engaging the same, the initial displacement of the handle causing the first mentioned pawl to engage the ratchet of the 85 transmission through the medium of the engagement of the crank with the arm of the ratchet associated with the handle, the said pawl remaining in engagement with the ratchet of the transmission during the movement of the handle, said spring disengaging the pawl from the ratchet of the transmission when the handle is released.
26. In a controller, a casing, a circuit make and break mechanism including a movable contact in said casing, a mechanism in said casing for operating the movable contact a predetermined variable number of times, said mechanism comprising a spring having a winding and an unwinding end, 100 an operating handle on the outside of the casing having an initial movement before engaging the winding end of the spring, means controllable by the handle adapted to lock the unwinding end of the spring by the 105 initial displacement of the handle and retain said unwinding end locked until the handle is released, and means for transmitting the movement of the unwinding end to the contact.
27. In a controller, a casing, a circuit make and break mechanism including a movable contact in said casing, a mechanism in said casing for operating the movable contact a predetermined, variable number of 110 times, said mechanism comprising a coil spring having a winding end and an unwinding end, an operating handle on the outside of the casing having an initial movement before engaging the winding end 115 of the spring, means controllable by the handle adapted to lock the unwinding end of the spring by the initial displacement of

- the handle and retain said unwinding end locked until the handle is released, means for transmitting the movement of the unwinding end to the contact, and a regulator 5 associated with the means for transmitting the movement from the unwinding end to the contact whereby the speed thereof is regulated.
28. In a controller, a casing, a tubular standard in the axis thereof projecting through the top of the casing, a circuit make and break mechanism, including a movable contact, in said casing, a mechanism on said standard in said casing for operating the movable contact a predetermined variable number of times, a pair of auxiliary contacts operable through the tubular standard for making and breaking the circuit independently of the mechanism.
29. In a controller, a casing, a tubular standard in the axis thereof projecting through the top of the casing, a circuit make and break mechanism in said casing, including a movable contact and a mechanism on the standard in said casing for operating the movable contact a predetermined variable number of times, a resilient auxiliary contact facing the bore of the standard adjacent the bottom of the casing, a second auxiliary contact spaced from the first contact, a plunger in said tubular standard, and an insulating member connecting the plunger to the movable contact.
30. In a controller, a casing, a tubular standard in the axis thereof projecting through the top of the casing, a circuit make and break mechanism in said casing, including a movable contact and a mechanism on the standard for operating the movable contact a predetermined variable number of times, a pair of auxiliary contacts normally separated at the bottom of said casing in alignment with the bore of the standard, a plunger in said tubular standard whereby said auxiliary contacts can be brought together, and a member secured to the standard forming simultaneously a retainer for
- the plunger in the standard and the mechanism on the standard.
31. In a controller, a casing, a movable contact therein, a spring having winding and unwinding ends in said casing, an operating handle on the outside of said casing, means associated with the handle and spring whereby the said handle has an initial movement before engaging the winding end of the spring, means associated with the unwinding end of the spring for transmitting the movement thereof to said movable contact, means controllable by the handle and operable by the initial displacement thereof whereby the transmission means are locked until the handle is released, and means automatically releasing said transmission when said handle is released, whereby the said transmission becomes operative under the action of the unwinding end of the spring.
32. In a controller, circuit make and break means including a movable contact and a mechanism for operating the movable contact, said mechanism comprising manually operable means, a spring having a winding and an unwinding end, said manually operable means being adapted to engage the winding end of the spring after receiving an initial displacement, means controlled by the initial movement of the manually operable means whereby the unwinding end is locked while the winding end is moved, means for retracting the manually operable means after the same has been released, whereby the winding end of the spring is locked while the unwinding end is free to move, and means for transmitting the unwinding motion of the spring to the movable contact.
- In testimony whereof I have signed my name to this specification in the presence of two subscribing witnesses.
- ALBERT STERN.
